PNEUMATIC ASH REMOVER

John K. Williams, York, Pa.

Application September 7, 1939, Serial No. 293,828

4 Claims. (Cl. 126—242)

This invention relates to pneumatic apparatus for conveying loose granular or pulverous materials and more particularly for removing and conveying ashes from furnaces, stoves or similar devices and depositing them in a receptacle.

The main object of the invention is to provide means for conveying loose or pulverized material, such as dust or ashes, from one point to another without any dust whatever leaking into the atmosphere from the conveyor system. Specifically it is an object of the invention to remove ashes from the ash pit of a furnace or stove and to convey the ashes to an ash receptacle inside or outside of the building without any ashes or dust leaking into the atmosphere either within the building or outside of the building. Another object of the invention is to provide efficient means for introducing pulverous material such as ashes into a closed conveyor circuit.

An objection to the older pneumatic ash conveyor system is that when employed with a stoker having the usual blower some method must be provided to close the ash conveyor conduit in order to prevent the operation of the draft from being affected. Therefore an important object of the invention is to provide a pneumatic ash conveyor which may be used with stoves or furnaces without affecting the operation of the draft in any way.

In carrying out my invention when employed as an ash remover I provide a substantially closed conduit circuit including a fan for driving the air through the circuit, an injector for pulling the ashes into the air stream circulating around the circuit and a settling chamber where the ashes are caught in a receptacle such as an ash can or storage bin. In addition the circuit may be provided with filters or dust traps whenever desired, particularly at the outlet of the settling chamber which outlet is connected to the fan whereby the fan handles only clean air which it drives through the circuit toward the ash intake located in the ash pit of the furnace.

In the drawing:

Figure 1 is a diagrammatic showing of my ash conveyor system connected with a furnace.

Figure 2 is an enlarged vertical section of the usual ash pit of a furnace, showing my improved device for introducing the ashes into the conveyor circuit.

Figure 3 is a vertical section of one type of ash receptacle or settling chamber showing how the conduits may be associated with the filter cover.

Referring to Figure 1, the furnace 10 is shown installed in a room having a wall 12 through which the conveyor conduit 14 and the return conduit 16 lead to and from an ash receptacle or settling chamber 18 which may be an ordinary ash can or a storage bin. The conduit 14

carries ash laden air from the sub ash pit 15 of the furnace 10 directly to the receptacle 18 where practically all of the ashes are precipitated while the return conduit 16 carries air from the filter unit 19 in the top 20 of the receptacle to the circulating fan 22 which drives the clean air through the high pressure or return conduit 24 to the injector nozzle 25, the end of which is spaced from the flared ash receiving mouth 26 of the discharge or conveyor conduit 14, the space being provided so as to allow ashes to move into the mouth.

When the fan is operating it will be seen that the pressure in the load carrying portion of the circuit, i. e. in the discharge line 14 is reduced thereby creating a suction at the space just mentioned with the result that ashes are drawn into the mouth 26 and this action is enhanced by the jet of air from the nozzle 25. One of the advantages of the system is that the pressure in the portion 14 of the circuit which carries the ash-laden air is at all times below atmospheric pressure so that there will never be any leakage of dust into the atmosphere from the conveyor or from the ash receptacle. The only part of the circuit from which air may leak into the atmosphere is the high pressure portion between the fan and the nozzle but the air in this portion is cleaned so that leakage is not objectionable except from the standpoint of efficiency. The terms "high pressure" and "low pressure" are relative and used primarily for convenience, since actually the pressures are usually not greatly different from atmospheric.

The injector feeder may be located in the ash pit 27 usually provided in the furnace as shown in Figure 2 but I prefer to install the feeder below the surface of the floor 30 as shown in Figure 1. When thus installing the feeder or intake below the floor level it is best to provide a substantial ash hopper 15. A grate 34 may be installed over the hopper 15 so as to prevent large clinkers or unburned coal from dropping into the feeder which might cause a stoppage; these clinkers and the like may be removed in the ordinary manner or they may be crushed and forced through the grate 34. It is best to slope the walls of the sub-pit as shown so that the ashes will gravitate to the mouth 26 of the discharge conduit.

The ash receptacle 18 is preferably located outside the furnace room or better still outside of the house where it may be reached for emptying without the necessity of entering the furnace room. The receptacle may be an ash can of ordinary construction but is provided with a removable filter cover 20 in which is secured a removable filter unit 19, preferably made of material such as matted fibers of vegetable or mineral composition. The end 37 of discharge con-

duit 14 is secured in the cover for admitting the ash-laden air directly into the chamber where most of the ashes precipitate. The intake end 38 of the return conduit 16 is located above the filter and is provided with several openings for drawing air through the filter material into the return conduit which conducts it to the fan 22. The cover 20 should have an air-tight fit with the can 18 to increase the efficiency of the system 10 and for this reason it is advisable to provide a gasket 39 around the rim of the cover. Although an ash can is shown in Figure 3 it is to be understood that a large storage space may be provided in order to make it unnecessary to remove the 15 ashes except at long intervals and perhaps at the end of the heating season. It is to be understood that the conduits 14, 16, 24 may be of any desired construction for example ordinary sheet metal pipe of the kind commonly used to transmit air but the terminal sections of the conduit 20 between the ash can and the wall 12 are preferably as indicated in Figure 3 of flexible metal hose to facilitate removal of the cover from the can when emptying ashes.

25 Although a fiber filter unit is shown in the drawing it is to be understood that any other type of dust removing device may be employed in the circuit so as to insure clean air being returned to the fan and to the high pressure side of the 30 circuit. If necessary or desirable additional filters such as shown at 40 and 41 (Figure 1) may be inserted in the suction or low pressure portion of the return conduit 16.

After a period of operation the filtering unit 35 19 when consisting of matted fibers may become clogged with dust. I find that most of the dust may be removed from the filter units by reversing the air flow through the circuit for a short time and for this reason where it is impractical 40 to reverse the fan it is desirable to provide cross-over connections 43 and 45 with valves 47 and 48 and also valves in the circuit at 50 and 51. During normal ash removal operation the valves 50 and 51 are open while the other two valves are 45 closed but when it is desired to reverse the flow of air I open the valves 47 and 48 and close the valves 50 and 51.

It is best to carry on the filter cleaning operation when the ash receptacle is empty and 50 the reverse of air flow should not extend for over a period of more than a minute or two which is usually sufficient time to remove most of the dust, especially if the filter unit 19 is tapped lightly with a hammer or other instrument to loosen the 55 dust. Where it is found that a longer period of air reversal is necessary then it may be desirable to provide a valved exhaust outlet 54 and a cut-off valve 55 in the conduit 14; during air reversal with this equipment in the system the valve 55 60 is closed and the door 56 of the ash pit is opened, so as not to affect the draft. If desired a filtering device may be inserted in the conduit 24 as indicated at 62 to prevent dust from entering the fan during reversal of air flow.

65 Where it is undesirable to exhaust into the air then a filter by-pass 58 may be provided around the valve 55 and this by-pass should have valves as at 60 and 61. When the circuit is provided with the by-pass 58 the open exhaust 54 may be 70 omitted. By closing the valve 55 and opening the valves 60 and 61 the reverse air current is filtered in the by-pass and the filter cleaning may be continued as long as desired, it being understood of course that the ash pit door is closed 75 when the by-pass is used instead of the exhaust.

The air reversal mechanism 43 to 51, the exhaust connection 54 and the by-pass 58 and valves 55, 60 and 61 are all optional as fairly satisfactory results may be obtained by merely tapping on the lid 20 while the fan is stopped, and when this does not remove most of the dust the filter unit 19 may be removed from the lid and renovated by any known method.

Instead of the by-pass 60, 61 I find it more convenient in some installations to use a by-pass 10 around the furnace as shown at 64 in Figure 2 and having a valve 65 that is normally closed but which may be opened when cleaning the filter 19, at which time the valve 66 in the conduit 14 should be closed. This by-pass and valves 65 and 15 15 66 are also optional as other means may be adopted for cleaning the filters without departing from my invention.

A great advantage of my system is that it does not affect the operation of the furnace whether 20 the furnace be hand fired, with or without a blower or is fired by means of a stoker having the usual blower. My system will operate with any type of air feed used with the furnace whether 25 natural draft, blower or other device.

When my system is employed in a furnace equipped with a stoker it will be understood, of course, that the intake will be installed in a manner to receive ashes from the retort and it may sometimes be necessary to sink the hopper 15 to 30 one side of the furnace so that the ashes may easily gravitate into the air stream.

I have shown my ash removal and conveyor system associated with a domestic heating plant because it is in such plants that my invention 35 will probably have its greatest use but my invention is not limited to any size or type of solid fuel burner and is adapted for use in all plants wherever ash removal is necessary.

What I claim is:

1. The combination in a device for removing ashes from a dwelling stove or furnace; of an ash pit having an exit opening, an air injector nozzle spaced from and discharging into said ash pit opening, an ash receptacle having a removable 45 cover, a blower conduit discharging high pressure air to said nozzle and withdrawing low pressure air from the cover, filter means in said cover between the major portion of the receptacle and the withdrawing end of the conduit, and an intermediate pressure conduit conveying ashes from 50 said exit opening through said cover to the receptacle.

2. The device of claim 1 including air reversing means for driving dust out of said filter means 55 and means for short-circuiting the nozzle and the exit opening during reversal of air flow.

3. An ash receptacle cover substantially filled with ash filtering material, an exhaust pipe located horizontally between the cover and the filtering material, a discharge pipe projecting vertically and centrally from the cover on its open side, and a flexible connection to each of said pipes proximate the side edge of the cover to facilitate movement of the cover with respect 65 to the ash receptacle which it covers.

4. In combination, an ash pit having an exit opening, a blower, a high pressure conduit discharging air from said blower to said ash pit exit opening, a lower pressure conduit connecting the 70 blower intake with said exit opening, a filter within said lower pressure conduit, and means for reversing the direction of flow of air from the blower thru said conduits to clean the filter.
